US00D783635S

(12) **United States Design Patent** (10) Patent No.: **US D783,635 S**
(45) Date of Patent: **** Apr. 11, 2017**

(54) **PORTION OF A DISPLAY SCREEN WITH ICON**

(71) Applicant: **HTC Corporation**, Taoyuan (TW)

(72) Inventor: **Chieh-Tun Yang**, Taoyuan (TW)

(73) Assignee: **HTC Corporation**, Taoyuan (TW)

(**) Term: **15 Years**

(21) Appl. No.: **29/532,020**

(22) Filed: **Jul. 1, 2015**

(30) **Foreign Application Priority Data**

Feb. 25, 2015 (CN) 2015 3 0049138

(51) **LOC (10) Cl.** **14-04**

(52) **U.S. Cl.**

USPC **D14/485**

(58) **Field of Classification Search**

USPC D14/485-495

CPC ... G06F 3/0481; G06F 3/04817; G06T 13/80;
G06T 15/02; H04N 1/00424

(57) **CLAIM**

The ornamental design for a portion of a display screen with icon, as shown and described.

DESCRIPTION

FIGURE is a front view of a portion of a display screen with icon showing my new design.

The broken line showing of a portion of the display screen is for the purpose of illustrating environmental structure and forms no part of the claimed design.
